UNITED STATES PATENT OFFICE.

CHARLES H. ATKINS, OF PALMER, MASSACHUSETTS.

PRESSURE PUMP.

1,416,314.

Specification of Letters Patent. Patented May 16, 1922.

Application filed May 13, 1920. Serial No. 381,105.

To all whom it may concern:

Be it known that I, CHARLES H. ATKINS, a citizen of the United States, and residing at Palmer, in the county of Hampden and 5 Commonwealth of Massachusetts, have invented certain new and useful Improvements in Pressure Pumps, of which the following is a specification.

This invention relates to pressure pumps 10 for supplying liquid fuel under pressure to an internal combustion engine, and has for an object to provide a pump for the purpose of producing relatively high pressures and of producing relatively high pressures and which can be operated at high speed. An 15 other object of the invention is to provide a pump without moving valves, and without packing glands, by adopting the principle of oscillating cylinders to cover and uncover the suction and discharge ports. A further 20 object is to provide a pump of this type which is simple in construction, easily assembled and disassembled and one that is not likely to leak under high pressures when in operation. Other objects of the invention 25 will be understood from the following specification and drawings, in which—

Fig. 1 is a plan view of the pump with the cover of the inclosing casing removed, and showing the operating mechanism with- 30 in the casing.

Fig. 2 is a cross sectional view of Fig. 1 through the axis of one of the pump cylinders and on a vertical plane passing through the axis of the piston or plunger of the 35 pump.

Fig. 3 is a horizontal sectional view on a plane passing through the center line of the plungers and pump cylinders.

Fig. 4 is a vertical sectional view of the 40 cylinders and valve mechanism with certain parts in section, and on a plane passing through the pump cylinders and at right angles to the axis of the cylinders.

Fig. 5 is a detail view of the valve, or suc- 45 tion and discharge ports.

Referring to the drawings in detail: The pump is driven from the main shaft 13 running in the bearings 14 and 15 and supported by the enclosing casing 11. 16, 17, 18, and 50 19, indicate the hubs of eccentrics similar to that indicated at 20 in Fig. 2, which are secured to shaft 13 and rotate therewith. Each eccentric is provided with an eccentric 55 strap 21 to which the pistons or plungers 22, 23, 24, and 25 are secured. These plungers, therefore, have a reciprocating motion im-

parted thereto when the shaft 13 is rotated. The plungers 22, 23, 24, and 25 are recipro- 60 cated, or move back and forth, in the cylinders 26, 27, 28, and 29 respectively, and as the shaft 13 is rotated, these cylinders are simultaneously oscillated, or have a rocking motion, in the chambers 34, 35, and 36 which are supported from the casing 11 by the integral extensions 31, 32, and 33 respectively. 65 (See Fig. 3.)

Referring now to the port mechanism of the pump which is shown in Figs. 3 and 5. The integral chambers 34 and 35 are each provided with a bushing 41 in which each 70 of the port members 44 fits tightly and are secured in place by means of the pins 45. The port members are slightly shorter than the bushings, leaving recessed spaces 39 at their ends, into which the disc shaped faces 75 37 and 38 of the cylinders 26, 27, 28, and 29 fit and turn as shown in Figs. 3 and 4. Face 38 is a ground fit against the face of the port member 44, and is maintained tightly in this position by the expansion coil spring 80 43 in chamber 36. This coil spring is enclosed within the spacer bushing 42 which forms a bearing for the opposite hub of the oscillating cylinder 27, to maintain it in alignment. The oscillating cylinders are as- 85 sembled with a spring on one side and a port member on the other, alternately, as shown, for any number of units for the purpose of maintaining an oil tight fit between the ports, as will be described.

The liquid fuel supply pipe is connected to a nipple 51, and the discharge pipes are connected to the nipples 54 and 57. The supply feeds through passage 52 to the cross- 90 passage 53 in the port member 44. The discharge to the nipple 54 connects by passage 55 to the cross-passage 56 in the port mem- 95 ber 44 and the nipple 57 connects by pas- 100 sage 58 to cross-passage 59 opening to the other side of port member 44.

The plungers comprise a rod of reduced diameter 62 on their upper end, fitting a cor- 105 respondingly sized bore in the cylinder heads. This difference in diameter between the larger diameter of the plunger proper and the rod provides a compression cham- 110 ber 61 above the plunger proper through which the plunger acts.

The plunger and rod, it will be noted, have a comparatively long bearing in the cylinder bore, and, in consequence, do not require packing to prevent leakage.

- The compression chamber 61 has a port 60 on the face 38 adjacent the port member 44, which in one position, aligns with the passage leading to the fuel supply pipe 51, 5 and in another position, aligns with the passage leading to one of the discharge pipes 54 or 57. The relative position of the supply passage 53 in the port member 44 is shown by line *a*, Fig. 5; and the position of 10 the discharge pipe is shown by line *b*. The extension 32, Fig. 3 is a section taken on the line *b* and the extension 32 is a section taken on line *a*, as indicated on the port member, Fig. 5.
- 15 When the plunger moves downwards, the cylinder is oscillated in the direction which aligns the port 60 with the fuel supply passage 53, thereby filling the compression chamber 61 with the liquid fuel. Continued 20 rotation of shaft 13 oscillates the cylinder back, closing the supply connection and aligning port 60 with discharge passage 56 on the outward stroke of the plunger, thereby discharging the liquid fuel in chamber 61.
- 25 It is to be understood that the discharge port opens when the plunger reaches the end of its stroke and begins to return.

A separate set of discharge passages 56 and 59 are provided in the fixed port member 30 44 so that each face of this member may be used for an independent cylinder.

The port member 44, and in fact any part of the port mechanism is easily replaced by moving the half section of chambers 34, 35, or 36. Moreover, these parts are easily made, being produced largely by a turning process of machinery.

One of the uses of the pump is to supply a charge of liquid fuel under high pressure 40 to internal combustion engines on the Diesel principle.

In operation, as the plungers are drawn inward, the cylinders are at the same time oscillated to cause the inlet port 60 to register with the annular space 61, thereby drawing in or allowing the liquid fuel to fill this space; as the plunger starts to return the cylinder closes the port 60, the fuel confined in the space 61 is subjected to pressure. When the pressure is sufficiently high, the outlet port, 56 or 59, being open permits the liquid fuel to escape into the cylinder of the engine. Since liquids are practically incompressible, it is important that the timing 50 of opening and closing the ports be designed with great accuracy. It should be stated that when the cylinders and plungers are in the horizontal position shown in Figs. 2 and 4 all of the ports are closed, but when the 60 cylinder oscillates in either direction, either the inlet or delivery port will be instantly opened on account of the close arrangement of the ports, as shown in Figs. 4 and 5. This is necessary on account of the incom- 65 pressibility of the liquid fuel.

What I claim is:

1. In a pressure pump of the class described, in combination, an oscillating cylinder having a compression chamber and a plunger chamber of different diameters and 70 a port located midway of its length and in the compression chamber only, of a plunger of different diameters operating in said chambers, a stationary port member having a supply orifice and a discharge orifice, the 75 port in said cylinder in one of its positions having communication with said compression chamber and with said supply orifice and in another one of its positions said chamber is in communication with said discharge orifice, and means for operating said cylinder and plunger. 80

2. In combination, a plurality of oscillating cylinders having ports therein, means for spacing them away from each other and 85 including members having inlet and exhaust ports therein which register with the ports in the cylinders as they are oscillated, other members having means therein for forcing the cylinders against the first mentioned 90 members.

3. A pressure pump for the purpose described comprising in combination, a plurality of cylinders, means for spacing the same from each other, said means including 95 expansion springs and blocks formed with ports therein which communicate with the cylinders.

4. In combination, a shaft, of a plurality of plungers, eccentric connections between 100 the shaft and plungers for operating the plungers, a plurality of pivotally mounted cylinders in which said plungers operate to impart an oscillating movement thereto, and each having a compression chamber, port 105 members between said cylinders, springs for holding the cylinders to their seats with said port members, a supply orifice and a discharge orifice in said port member, means for connecting said orifices alternately with 110 said compression chamber.

5. In combination, a shaft, of a plurality of plungers, eccentric connections for operating the plungers from said shaft, a plurality of oscillating cylinders in which said 115 plungers operate, and each having a compression chamber, port members spaced between said cylinders and each having a plurality of supply and discharge orifices, springs spaced between said cylinders and 120 members, and means for connecting said supply and discharge orifices alternately with said compression chamber and said springs serving to hold said cylinders against said port members.

6. In a pressure pump of the class described, in combination, a member having an inlet and an outlet passage, a port member snugly fitting said member and having matched inlet and outlet passages terminating on its 130

- face, an oscillating cylinder having a compression chamber and a circular face to match the face of said port member and fitting partially within said member, means 5 for connecting said inlet and said outlet passages alternately with said compression chamber and a plunger operating in said cylinder for imparting pressure to the liquid in said chamber.
- 10 7. In a pressure pump of the class described, in combination, a plurality of chamber members having inlet and outlet passages and other members without passages, the chamber members being spaced alternately with the other members without passages, port members fitting within said chambers with said passages and having matched passages terminating on their faces, oscillating cylinders, each having compression chambers and double circular pivotal faces, one of said faces fitting against said port member and the other of said faces fitting within said adjoining other member, means for connecting said passages with said 25 compression chambers, and plungers operating in said cylinders.
8. In a pressure pump, the combination, of a cylinder formed with a bore of different diameters, a plunger therein, and 30 formed to fit the different diameters of the bore, that portion of the plunger which is of the smaller diameter being partially located within the bore of larger diameter and serving to subject a fluid to pressure in 35 that portion when the plunger is operated, means for operating the plunger, and simultaneously oscillating the cylinder, and means for admitting the fluid to said portion of the bore and for permitting the same to escape after compression when the cylinder 40 and plunger are operated.
9. In a fluid pressure pump, the combination, of a pivotally mounted cylinder formed with a bore of different diameters, a plunger formed with a shoulder and located therein; means for reciprocating the plunger and for oscillating the cylinder, the smaller part of the plunger serving to provide an annular compression chamber, the cylinder having a port leading to said chamber, a member formed with a supply and discharge port which lines up with the port in the cylinder to admit the fluid which is to be pumped to the chamber and to discharge it from the chamber when the plunger has 50 imparted the necessary pressure thereto and simultaneously with the oscillating movements.
10. In a pressure pump, the combination, with a plurality of oscillating cylinders 60 having ports therein, members having inlet and exhaust ports therein for communicating with the ports in the cylinder which are located in the opposite ends of the members, springs between the cylinders for forcing 65 the same against the port members, and means including plungers for oscillating the cylinders, all constructed and arranged for forcing liquid under pressure from the cylinders as the same are operated.

CHARLES H. ATKINS.
